UNITED STATES PATENT OFFICE.

CHARLES T. HUBBARTT, OF ST. LOUIS, MISSOURI.

DESIGN FOR A SIGN-PLATE.

SPECIFICATION forming part of Design No. 24,188, dated April 9, 1895.

Application filed March 7, 1895. Serial No. 540,898. Term of patent 14 years.

To all whom it may concern:

Be it known that I, CHARLES T. HUBBARTT, a citizen of the United States, residing at the city of St. Louis, State of Missouri, have invented and produced a certain new and original Design for Sign-Plates, of which the following is a full, clear, and exact description, reference being had to the accompanying drawings, forming part of this specification, to wherein—

Figure 1 is a plan view of a sign plate ornamented and configured according to my new and original design. Fig. 2 is a cross-sectional view taken on line 2—2 Fig. 1.

This invention relates to a new and useful design for sign plates, the general appearance being in the shape of a mortar and pestle.

The design is of sheet material, which is

concavo-convexed. On the convexed face the plate is painted or otherwise provided with 20 lines to carry out the general effect of the design. The edges are brought to a point and are on the same plane. Letters or characters may be arranged on the design in any desired manner. 25

What I claim is—

The design for a sign-plate, substantially as herein shown and described.

In testimony whereof I hereunto affix my signature, in presence of two witnesses, this 30 2d day of March, 1895.

CHARLES T. HUBBARTT.

Witnesses:

F. R. CORNWALL,
HUGH K. WAGNER.
